UNITED STATES PATENT OFFICE.

CLINTON H. HANSON, OF CHICAGO, ILLINOIS, ASSIGNOR TO THE MOTOR PLAYER CORPORATION, OF CHICAGO, ILLINOIS, A CORPORATION OF ILLINOIS.

MEANS FOR ACTUATING PLAYER PIANOS.

Application filed September 6, 1922. Serial No. 586,450.

This invention pertains to improvements in vacuum producing devices such as are used for actuating the pneumatics of player pianos. The improvements contemplated 5 are adaptable for use with such suction producing devices as illustrated in Patent No. 1,320,224, issued October 28, 1919, to the Electora Manufacturing Company as assignee of George W. Garman, and such as 10 shown, described and claimed in my Patent No. 1,565,932 issued December 15, 1925.

Briefly such devices comprise a motor and fan unit which is operated at a high rate of speed, and is employed for exhausting air 15 from the windchest, which is directly connected with the actuating pneumatics of a player piano. One of the difficulties encountered with the operation of such unit is the silencing of the motor, without increasing the back pressure, and consequently 20 without decreasing the vacuum attained by the machine. Another difficulty is the provision for lubrication without the employment of a complicated construction.

Accordingly, my invention is directed toward the construction of a vacuum producing device which possesses a minimum number of parts, and is arranged in such manner as to eliminate the transmission of sound 30 waves incident to the operation of the unit. The invention is also concerned with the provision of a unit which may be readily dismantled and reassembled in the most expeditious manner.

The means for carrying out my invention will be hereinafter fully set forth in the following description, which pertains to the accompanying drawings, and the essential features will be summarized in the claims.

In the drawings, Fig. 1 is a vertical section through a machine having improvements embodying my invention; Figs. 2, 3 and 4 are sections taken on the lines 2—2; 3—3; 4—4 respectively in Fig. 1; Fig. 5 is 45 a bottom view of the power unit removed from the housing or container and showing the relative position of the flap valves thereon; Figs. 6, 7 and 8 are details in the nature of sections through various parts of the 50 power unit; and Fig. 9 is a view partly in section and partly in elevation showing the relative arrangement between the power unit and the housing therefor, the essential elements being shown somewhat separated.

One of the essential objects of my invention, as above stated, is to provide means for obtaining efficient sound insulation of a vacuum producing unit. Accordingly, I have shown a unit as embodying a motor having an armature 10 which is supported in bearings indicated generally at 11 and 12. These bearings are journaled at the top and bottom of the armature shaft 13 within a casing, part of which forms a motor frame 14. The lower part of the casing forms a housing 15. Fan blades mounted on the shaft 13 are indicated at 16, and are so arranged as to cause a current of air to flow downwardly through the motor, thence through the various fan chambers, and out of the bottom 70 chamber through ports 17. In this form of construction, the motor and fan become a unitary structure which may be handled as a unit to place it in the container or remove it therefrom. The combination of a motor 75 and fan will be hereinafter referred to as the "power unit".

To eliminate the noise or hum incident to the operation of the power unit, I provide a housing which entirely surrounds the unit 80 and is spaced therefrom by suitable sound insulating material. This housing is shown as embodying upper and lower sections 20 and 21 adapted to be joined in a plane transversely thereof. Each section may 85 comprise a hollow box-like wooden member so formed that when the unit is assembled within the housing, the top and bottom thereof is closed. The space intermediate the unit and the housing is filled with sound 90 insulating material. I have found that satisfactory results may be obtained by using a granular substance such as ground cork, saw dust, or granular rubber; this material being indicated at 25. The two sections 95 are held together by suitable means, such as corner plates indicated at 26, which are arranged to be attached to the sections above and below the plane of separation thereof.

The casing as heretofore stated has the lower part shaped to provide a fan housing. The upper part of the casing in the preferred form embodies a muffler 30 which is illustrated as a dome shaped member having a flange 31 which is held in abutting engagement with the lower portion of the casing as by spaced securing members 33. Thus when the muffler is attached to the fan hous-

ing, I provide a casing which is maintained in spaced relationship to the outer enclosing housing.

By making the casing principally of metal and by making the housing of wood, the housing is more impervious to the passage of sound waves therethrough than the casing. This tends to make the device more quiet in operation, and at the same time to 10 simplify the construction.

This muffler is preferably made of pliable material such as rubber which is sufficiently stiff or rigid to maintain its form and resist the suction pressure. This muffler provides 15 a cavity within the section 20 into which part of the power unit is adapted to extend, and also serves as a means for retaining the granular insulation out of contact with the power unit. To facilitate clamping of 20 the muffler 30 to the metallic casing 15, I may provide a metallic ring 32 which is shown as embedded in the upper surface of the flange 31 and is provided with threaded openings to engage screws 33, as 25 indicated particularly in Fig. 7. In this way the section 21 may be removed from the section 20, thus leaving the power unit attached to the other section. In the lower section, a muffler is indicated as a metallic 30 cup-shaped member 35 which extends beneath the power unit and is provided with an opening 38 which serves as an exhaust air passageway. The power unit may be held in spaced relation to the muffler 35 by means 35 of flexible cushion blocks 36 which rest upon the bottom member 35, and engage the under side of the fan blade casing 15.

The interior of the member 35, that is, the portion adjacent the vertical walls thereof, 40 may be lined with sound insulating material, as at 37, while across the bottom suitable means may be employed for preventing the insulating material 25 from entering the fan chamber, and at the same time for preventing dust and lint from entering the material 25. To this end, I have shown a wire screen 39 which is laid across the opening 38. This is particularly illustrated in Fig. 6. Above the screen 39, I have shown a 45 strainer 40 which is mounted on a removable member 41 whereby the strainer may be readily cleaned whenever desired. This removable member preferably comprises a ring which is adapted to engage the inner surface of the member 35.

As a further means for entrapping or deadening sound waves within the housing, I have shown two flap valves 45 which are mounted on the under side of the fan chamber and are adapted to be held in engagement therewith by suitable springs 46 which are held in place by securing member 47. Normally, the springs retain the flap valves 50 in engagement with the outer surface of the fan chamber whereby the ports 17 are closed,

thus retaining considerable noise within the machine when the piano is operated by means of the usual foot pedals. Then too, when the power unit is set in operation, the flap valves cause further baffling of the exhaust air, thus tending to reduce the transmission of sound waves into the atmosphere. 70

Air is admitted into the housing through a passageway 50 indicated in the side of the section 20. This passageway may 75 be formed by securing a flanged conduit 51 at the side of the housing, and by connecting said conduit to a nipple 52 projecting outwardly from the muffler 30. I may employ a flexible conduit 53 intermediate the 80 nipple and conduit 51 as indicated in Fig. 1. The outer end of the conduit 51 may be attached to a tube 54 which is arranged to be connected with the actuating pneumatics of a piano (not shown). 85

With this form of construction, the vacuum producing unit is practically free from any rigid connection to either section of the housing. Accordingly, the unit gradually settles into engagement with the cushioning 90 means 36. Since the supporting member 35 is embedded in the granular insulating material, it follows that the insulating material serves a three-fold function, namely;—a support for the power unit, a passageway for 95 the exhaust air, and a means for absorbing sound waves, thus effecting the silent operation of the machine. The insulating material in the upper section is preferably powdered or ground rubber, but in the lower 100 is preferably cork or sawdust. In this way, warm air from the motor and fan does not carry an offensive odor, which is likely to be given off by the rubber. 100

With the arrangement described, the 105 power unit may be readily removed by separating the housing adjacent the meeting edges of the sections. In Fig. 9, the separated sections with the power unit disposed therebetween illustrate the relation of the 110 associated parts. Accordingly, each section when removed comprises a member having a cavity therein into which part of the power unit is adapted to extend. It is desirable therefore, to effect such removal without disturbing the arrangement of the insulation. To this end, I may provide a fabric disc 60 as shown in Fig. 7 which extends between the flange 31 and the edges of the section 20, and a similar disc 61, 115 which extends between the muffler 35 and the edges of the lower section 21. To prevent contact between any of the metallic parts and the casing, I have shown a section of insulating material such as felt 62, disposed adjacent the plane of separation of the housing. This section preferably extends entirely around the marginal edges of the muffler, and serves to prevent the passage of air into the upper section of the 120 125 130

housing. Moreover by making the disc 60 of comparatively heavy fabric such as canvas and cementing it thoroughly to the flange 31 and also by clamping it to the felt 5 between the housing sections, then this disc will function to prevent rotation of the unit with reference to the housing upon starting of the motor. This allows the passageway 50 in the housing to be disposed out of alignment with the passageway in the casing 30 while the flexible tube 53 makes the operative connection in a satisfactory manner.

When the motor is set in operation, air is caused to flow through the usual operating pneumatics of the piano into the conduit 50, thence through the power unit as indicated by the arrows. Upon leaving the unit, the air passes through a strainer 40, screen 39 and thence through the granular 15 insulation in the lower section of the container, whence it is ejected through openings 70 adjacent the corners of the container. The inner walls of the container adjacent the openings are preferably covered by fabric indicated at 71 to prevent the passage 20 of granular material out of the container. In this way, the insulation provides a passageway for the air, and at the same time serves as an insulating medium to retain 25 sound waves within the container.

By constructing a vacuum producing device embodying my invention, the power unit may be assembled entirely independently of the container. This construction 35 permits the bearings to be readily lubricated without removing the motor armature or its associated mechanism from the support, forming the motor fan chamber, and without displacing the sound insulating material 40 intermediate the unit and housing.

I claim:

1. In a vacuum producing device for operating player pianos, the combination with a vacuum producing unit, of a casing 45 enclosing the unit, an enclosing housing spaced from the casing and having a vertical wall, a flexible inlet conduit connecting the housing and casing, said housing having outlet openings in said vertical wall, means 50 acting independently of the conduit for preventing rotation of the casing with reference to the housing when the unit is placed in operation, and said housing embodying material having a different rate of sound wave 55 conductivity than the casing material.

2. In a vacuum producing device for operating player pianos, the combination with a vacuum producing unit of a casing surrounding the unit and having inlet and 60 outlet apertures therein, a housing enclosing the casing and being spaced therefrom, granular sound insulating material packed closely between a portion of the casing and the housing, means connecting the housing 65 and the casing for preventing relative rota-

tive movement of the housing and casing when said unit is set into operation, a flexible air inlet conduit connecting the housing and casing, and means whereby said unit causes a moving jacket of air to flow into 70 the casing through the inlet, thence through the unit and to be discharged through said outlet, after passing through closely arranged particles of said insulation.

3. In a device for actuating the pneumatics of a player piano, the combination with a vacuum producing unit of a casing surrounding the unit, said casing having a portion thereof embodying material having greater resistance to the passage of sound 80 waves therethrough than the remaining portion thereof, a housing enclosing the casing, granular sound insulating material disposed between the housing and the casing, a flexible conduit providing communication between the interior of the casing and the exterior of the housing, and an air outlet in the housing, whereby a jacket of air is caused to flow through the insulation before 85 passing out of the housing.

4. A device for operating the pneumatics of a player piano comprising in combination, a housing having an inlet and an outlet port, a casing within the housing, one part of the casing embodying pliable material and another part of the casing embodying rigid material whereby one part of the casing presents a greater resistance to the passage of sound waves therethrough than another part of the casing, granular 100 sound insulating material disposed intermediate the housing and casing, means for conducting air into the casing through said inlet without contact with said insulation, and means whereby air passing through the 105 casing is caused to flow through the insulation.

5. In a device of the character described the combination with a vacuum producing unit, of a casing surrounding the unit, a housing enclosing the casing and comprising a pair of opposed separable sections joined intermediate the ends of the housing, sound insulating material disposed intermediate the housing and casing and closely 110 enveloping the casing, a flexible inlet passageway leading through the side of one of the sections of the housing and communicating with the interior of the casing, a discharge aperture in the side of the housing 115 in the other of said sections, the ends of said housing being closed, whereby air flowing through the unit is caused to follow a tortuous path around the casing and to flow directly through the insulation and out the 120 side of the housing.

6. In a device for actuating the pneumatics of a player piano, the combination with a vacuum producing unit, of a casing 130 surrounding the unit and having a portion

thereof formed of pliable material, an enclosing housing surrounding the casing, sound insulating material disposed intermediate the casing and housing and a 5 flexible conduit extending through the insulation and providing communication between the interior of the casing and the exterior of the casing.

7. In combination, a vacuum producing 10 unit, a casing therefor, said casing comprising a plurality of sections, at least one of the sections being made of pliable material, a housing for the casing, said housing comprising separable sections having openings 15 in the side thereof, an opening in one of the sections comprising an inlet passageway and an opening in the other of said sections comprising a discharge passageway, granular insulating material disposed between the 20 housing and casing, the pliable section of the casing comprising a wall for retaining the insulation in position when the housing is separated.

8. In combination, a vacuum producing 25 unit, a casing therefor, said casing comprising two separable sections, one section comprising a cup-shaped pliable member having a radial flange adjacent the rim thereof, a housing surrounding the casing, closely 30 packed granular insulation disposed intermediate the casing and housing, said insulation being retained by the cup-shaped section and the flange thereof.

9. In combination a vacuum producing 35 unit, a casing therefor, a cup-shaped baffle enclosing a portion of the casing, a housing disposed outside the baffle and closely packed granular insulating material between the baffle and housing, whereby air flowing 40 from the unit passes through the interstices between the particles of insulation.

10. In combination, a vacuum producing 45 unit, a casing therefor, a housing surrounding the casing and comprising a plurality of separable sections joined intermediately, the housing being more impervious to the passage of sound waves than the casing, closely packed granular insulating material between the casing and housing, a fabric connection 50 between the housing and casing for preventing relative angular movement of the casing with reference to the housing, said housing having air inlet and outlet openings intermediate the top and bottom thereof, a flexible 55 conduit connecting the casing to the inlet opening in the housing whereby air is restricted to a confined passage through the insulation upon entering the casing, and the air being discharged from the casing being caused to flow through the interstices between the particles of insulation, and being unconfined while flowing from the unit to the outlet opening in the housing.

11. In combination, a vacuum producing 60 unit, a casing therefor, a housing enclosing

the casing, said housing comprising a plurality of separable sections, granular insulation disposed within one section intermediate the housing and casing, means for preventing the circulation of air through the insulation within said section, granular insulation between the casing and the other of said sections and means whereby the air is caused to flow unconfined through the insulation in the last mentioned section. 70

12. In combination, a vacuum producing unit, a casing therefor, a housing surrounding the casing and comprising a pair of separable sections, granular insulating material disposed intermediate the casing and housing, said material being in close-fitting engagement with a portion of the casing and comprising a support therefor, said casing having a dome-shaped section of pliable material adapted to provide a retaining wall 80 for a portion of the insulation, means for connecting the pliable section to the remaining portion of the casing, and means for connecting the pliable section to the housing so as to prevent rotation of the casing when 85 the unit is in operation.

13. In combination, a vacuum producing unit, a casing therefor, a housing enclosing the casing and comprising a plurality of separable sections, granular sound insulating 90 material intermediate the casing and housing, means for retaining the insulation in one section in position independently of the insulation in the other section, a conduit providing a passageway for air between the 95 housing and the casing, means whereby the insulation surrounding the conduit embodies numerous dead air cells, and means for permitting the passage of air directly through the insulation of the other section, whereby 100 circulation of air is maintained there-through.

14. In combination, a vacuum producing unit, a casing therefor, a housing enclosing the casing, the casing comprising two cooperating sections and said housing comprising two cooperating sections, all of said sections being separable on substantially the same plane, granular insulating material intermediate the housing and casing and a flexible air inlet conduit extending between one section of the housing and one section of the casing. 110

15. In combination, a vacuum producing unit, a pair of opposed cup-shaped members disposed above and below the unit and providing a shell therefor, and a housing outside the shell, one of said members being formed of pliable material, whereby greater resistance is offered to the passage of sound waves therethrough than through the other 120 of said members.

16. In a device of the class described, the combination with a vacuum producing unit, of a housing therefor comprising separable sections, each having a cavity adapted to 130

receive part of the unit, sound insulating material intermediate the unit and sections for providing an air passageway, a cup-shaped baffle outside the unit and within 5 one of the sections and a removable strainer carried by said baffle.

17. In a device of the class described, the combination with a vacuum producing unit, of a casing therefor, at least a portion of 10 said casing being of pliable material, a housing, and a conduit connecting the housing to the casing.

18. In a device of the class described, the combination with a vacuum producing unit, 15 of a pliable member surrounding a part of the unit and spaced therefrom to provide an

air passageway, a housing surrounding said member, sound insulating material disposed intermediate the member and housing, and a passageway for providing communication 20 between the exterior of the housing and the interior of said member.

19. In a device of the class described, the combination with a vacuum producing unit embodying a motor and fan chamber, a casing comprising a pliable member surrounding the motor portion of the unit, and a 25 housing enclosing the casing.

In testimony whereof, I hereunto affix my signature.

CLINTON H. HANSON.
